(57) **CLAIM**

I claim an ornamental design for the electronic smoking device, as shown and described.

DESCRIPTION

FIG. 1 is a perspective view of an electronic smoking device showing my new design;

FIG. 2 is a bottom view thereof;

FIG. 3 is a top view thereof;

FIG. 4 is a left side elevation view thereof; and,

FIG. 5 is a right side elevation view thereof.

The broken lines in the drawings depict parts of the electronic smoking device that form no part of the claimed design.
